CLAIM

The ornamental design for a device for filling multiple water balloons, as shown and described.

DESCRIPTION

FIG. 1 is a front, right and top perspective view of a device for filling multiple water balloons showing my new design; FIG. 2 is a front perspective view thereof;

FIG. 3 is a rear side view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the device for filling multiple water balloons that form no part of the claimed design.

1 Claim, 7 Drawing Sheets
